(57) **CLAIM**

The ornamental design for a teat, as shown and described.

DESCRIPTION

FIG. 1 is a front end view of a teat in accordance with the present invention;

FIG. 2 is a top plan thereof;

FIG. 3 is a bottom plan view thereof;

FIG. 4 is a side view thereof taken from the right side of FIG. 1, the side view taken from the left side thereof is a mirror image of FIG. 4;

FIG. 5 is a perspective view thereof taken from the upper left side of FIG. 1;

FIG. 6 is a perspective view thereof taken from the left upper side of FIG. 1;

FIG. 7 is a perspective view thereof taken from the lower right side of FIG. 1; and,

FIG. 8 is a perspective view thereof taken from the upper right rear end of FIG. 1.

The portions of the Figures shown in broken lines disclose environmental structure and form no part of the claimed design.
